(57) **CLAIM**

We claim the ornamental design for an AC/DC adapter, as shown and described.

DESCRIPTION

FIG. 1 is a top perspective view of our new design of an AC/DC adapter;

FIG. 2 is a bottom perspective view thereof;

FIG. 3 is a top view thereof;

FIG. 4 is a bottom view thereof;

FIG. 5 is a side view thereof; and,

FIG. 6 is a front view thereof.

(Continued)

The broken lines in the above described FIGS. 1-6 depict environmental matter and form no part of the claimed design.

1 Claim, 6 Drawing Sheets
